(57) **CLAIM**

The ornamental design for a seal member, as shown and described.

DESCRIPTION

FIG. 1 is a perspective view of a seal member, showing our new design;

FIG. 2 is a Front view thereof, the opposite side view being identical;

FIG. 3 is a Top view thereof;

FIG. 4 is a Bottom view thereof;

FIG. 5 is a Right side view thereof, the opposite side view being identical;

FIG. 6 is a cross-sectional view thereof taken along line 6-6 shown in FIG. 2; and,

FIG. 7 is an enlarged detail view of area 7 in FIG. 6.

The broken lines shown in the drawings represent portions of the seal member that form no part of the claimed design. The dash-dot-broken lines shown in the drawings depict boundaries of the claim and form no part thereof. The
